UNITED STATES PATENT OFFICE.

JOSEPH EDWARD SMITH, OF FORT WAYNE, INDIANA.

RAILWAY-RAIL ANCHOR.

Application filed December 24, 1926. Serial No. 156,787.

This invention relates to improvements in railway rail anchors of the type applied to the foot of the rail and in contact with the tie for the purpose of preventing creeping 5 of the rail. The object of the improvement is to provide a rail anchor constructed of a single piece of metal and so formed as to admit of its being sprung into position on the rail. Another object of the invention is 10 to so construct the anchor that it will remain firmly clamped in connection with the foot of the rail and not be effected by vibration.

These objects are accomplished by the 15 construction illustrated in the accompanying drawings, in which:—

Fig. 1 is a cross section of a railway rail with an anchor embodying the invention applied thereto; and

Fig. 2 is an elevation showing the rail and anchor in a plane at right angles to that of Fig. 1.

The characters appearing in the description refer to parts shown in the drawings 25 and designated thereon by corresponding characters.

The invention consists of an anchor made from a bar of spring steel and formed with a straight arm 1, with a hook 2 at one end 30 of the arm and a contiguous spring bow 3 at the opposite end of the arm, there being formed at the end of the bow a T-head 4 having slotted side jaws 5 spaced apart so as to accommodate the arm 1 therebetween. Each 35 jaw 5 has in its inner edge a slot 6 located so that the upper face of the arm 1 is spaced slightly above the bottom of said slots, whereby the arm is held in contact with the bottom of the rail when the jaws are applied 40 to the corresponding flange of the rail. The bow 3 is made of greater width than the T-head so that each side of the bow extends in a vertical plane spaced from the vertical plane of the corresponding jaw.

In utilizing the invention the jaws 5 are first applied to one of the flanges 9 of the railway rail 8 with the arm 1 extending under the rail, and the hook 2 is then sprung outwardly so as to clear the edge of the flange 50 7 of the rail by applying force against the opposite end of the arm 1, whereupon, by elevating the arm the hook is sprung into position on the flange 7. When the anchor is thus positioned the arm 1 is held flat 55 against the foot of the rail, and the T-head 4 with which the arm has sliding contact

bears against the bottom face of said arm, and the tension of the spring bow is such that the jaws are forcefully held in position on the flange 9 of the rail. In this manner 60 the foot of the rail is gripped between the hook 2 and the slotted jaws 5 with resistant force exerted by the spring bow.

In applying the anchor to the rail it is so placed that the one side of the bow bears 65 against the tie 10 so that endwise movement of the rail in one direction is thereby obstructed. When the rail tends to creep, the spring bow 3 bears with more or less force 70 against the tie which tends to tilt the cross head and contiguous end of the arm 1, thus causing a binding action upon the arm between the bottom of the rail and the top of the T-head, and a corresponding binding 75 action upon the flange 9 of the rail between the arm and the jaws. Thus, slippage between the rail and anchor is frustrated.

What I claim is:—

1. A rail anchor made of a single piece of spring plate metal formed with a straight 80 arm with a hook at one end thereof and a contiguous spring bow at its opposite end; a T-head formed at one end of the bow, which head has sliding contact with said arm; and a pair of slotted jaws extending 85 from said head and spaced apart for the reception therebetween of said arm; said slots being so located that the bottom of each slot extends in a plane lower than the top of said arm. 90

2. A railway rail anchor made of a bar of spring metal, one portion of which constitutes a straight arm with a hook at one end thereof, that portion of the bar contiguous with the opposite end of said arm constituting 95 a spring bow, there being formed at the end of the bow a pair of slotted jaws between which said arm extends, said hook and the jaws being applicable to the opposite flanges of the foot of the rail so as to 100 grip the rail under resistant force applied by said bow.

3. A railway rail anchor one portion of which constitutes a hook arm, that portion contiguous with said arm opposite the hook 105 constituting a spring bow, there being at the end of said bow a pair of spaced jaws between which said arm extends, the hook of said arm, and said jaws being applicable to the opposite flanges of the foot of the 110 rail so as to grip said rail under resistant force applied by said spring bow, one of said

flanges of the rail and said arm being clamped between the end of said bow and said jaws.

4. A railway rail anchor having a spring bow, a hook arm contiguous with said bow; and a pair of slotted jaws extending from that end of said bow opposite the connection of said bow with said arm, said jaws being spaced apart and extending astride said arm, 5 said jaws being applicable to one flange of the rail, and said hook arm extending be-

neath said rail and engaging the opposite flange thereof, said hooked arm and jaws having gripping relation with said flanges under resistant force applied by said spring bow, and said jaws and arm having binding action on the flange of the rail to which said jaws are applied when said spring bow is tilted. ¹⁵

In testimony whereof I affix my signature.

JOSEPH EDWARD SMITH.
